UNITED STATES PATENT OFFICE.

WILLIAM H. MAXWELL AND J. MILTON STEARNS, JR., OF BROOKLYN, N. Y.

METHOD OF AND APPLIANCE FOR CONTROLLING AND PREVENTING FIRES IN BUILDINGS.

SPECIFICATION forming part of Letters Patent No. 286,621, dated October 16, 1883.

Application filed April 21, 1882. (No model.)

To all whom it may concern:

Be it known that we, WILLIAM H. MAXWELL and J. MILTON STEARNS, Jr., both residing in the city of Brooklyn, Kings county, 5 and State of New York, have invented a new and improved system of preventing buildings from taking fire, and for extinguishing fire in buildings and preventing the spread of flame or fire in the interior thereof, of which the following is a specification.

The nature of our invention relates to a system and apparatus for suddenly closing a building or any given portion thereof, either to prevent fire from extending to it or inside 15 of it and to extinguish fire already therein.

The object of our invention is to provide with the ordinary appliances of a building such apparatus and machinery that the building threatened with injury or destruction by 20 fire, or already in combustion, can be suddenly closed, either entirely or in any part, and at the same time and by the same expenditure of force fire-extinguishing apparatus within 25 a building or attached thereto may be set in operation.

To enable others skilled in the art to make and use our invention, we will now proceed to describe the construction and operation of the same, and we hereby declare that the following 30 is a full and exact description thereof, reference being had to the accompanying drawings, and to the letters of reference marked thereon, the same forming a part of this specification.

35 To accomplish the results that we desire, we first state generally the method we employ, and then the character of the machinery to be employed in the utilization of the method.

We provide, first, that the shutters of the windows of the building shall be of a character to be readily closed, and therefor we employ preferably what is known as the "roller-shutter," and the same is also preferably constructed of iron or metal slats in well-known forms. The 40 shutters in each row of windows, considered 45 perpendicularly, are all connected together by a cable, preferably steel wire, or are so arranged as to their connection with such cable that they become so connected in operating the 50 machinery. To the cable is attached a weight, which, when allowed to act by gravity, will simultaneously close all the shutters of a per-

pendicular row of windows in a building or other apertures like windows. The cables, 55 weights, and shutters are all connected together by mechanical means, so that all can be operated simultaneously and from one point. Our further invention consists in that, by the operation of our method, as hereinbefore set forth, fire-extinguishing apparatus is set in 60 operation in the building. The method in full therefore consists in closing simultaneously all the shutters over apertures of a building by connecting the said shutters together, either permanently or temporarily, by a cable, moving 65 such cable in a proper direction to close such shutters by the operation of gravity in a weight or retractile tension in a spring, linking such cables together so as to be operated from one point, and setting in operation from 70 such point at the same time fire-extinguishing apparatus to extinguish fire in said building.

Reference being now had to the drawings, Figure 1 is a front elevation of a building fitted with our invention, the lower portion 75 being shown in section and the shutters in various positions. The several rows of windows are shown numbered 1 2 3 4 5, the shutters being shown in different positions in each row to more explicitly indicate the operation 80 of the other machinery. B B, &c., are the windows. D D D D D, &c., are the respective shutters to the windows, preferably roller-shutters. A represents the cable passing in front of each window, and terminating at its 85 lower extremity in a weight, W, which is preferably placed below the ground level outside of the building in an area surrounding such building; or in special areas or well-holes in proximity to the cellar-walls, for the especial 90 purpose of receiving such weights and cables. The cables ascend in front of or in proximity to their respective rows of shutters, as shown. In row 5 the shutters are fully open, and the position of the weight and 95 cable ready to operate is clearly indicated. In rows 3 4 the shutters are fully closed, and the weights are at their lowest points. The attachment of the cable to the shutter is by a cleat or fastening, preferably at the lower 100 portion of the shutter. Such attachment, if the shutters are all of the same height or depth of drop to close, may be permanent; but if windows and shutters are of diverse heights, as

is frequently the case, the attachment is by a catch operated by a button or projection upon the cable itself, such projection being so arranged and affixed to said cable before or in proximity to said row of windows as to connect with and clutch said shutters at the proper moment of time during the operation of the device, so that, whatever may be the different sizes of shutters in the row, they will all reach the closing-point at the same time. C C represents such projections as examples. X, Fig. 1, is a fire-extinguisher connected by pipe P (shown by dotted lines) with the different floors of the building. The dotted lines at right angles to the pipe P indicate necessary branch pipes to such floors. Such fire-extinguishing apparatus is set in operation by a lever, which is moved by a catch or clutch on cable of row of windows 3 in drawings. All the several cables are operated at once by the lever S, which disengages a clutch or catch on each of the cables to permit the descent of the weights W W, &c., when the apparatus is to close the shutters. The points of operation of the lever by a horizontal bar attached to it on the respective cables is at G G, &c.

In Fig. 2 we show a vertical section of a building fitted with our invention. In this sectional view a separate fire-extinguisher is shown for each floor of the building, and the arrangement of the cable inside the building is shown passing convenient pulleys at the top of the building and descending on the inside of the windows to operate the fire-extinguisher.

Fig. 3 is a perspective view of the cable A, with a projection or stop, H. G is the clutch, which is indicated at G G, &c., in drawings, Fig. 1, on the horizontal bar attached to lever S. The shutters are attached to the cable, either permanently, as before described, or temporarily, by a projection like m, operating on a ring attached to the shutter at the proper point, through which m will not pass, but the cable will freely pass. There are many ways in which such an attachment can be made; hence we do not limit ourselves to any one particular shape or design of weight, catch, shutter, ring, cleat, cable or cable attachment, lever, or lever bar or rod.

Fig. 4 shows how that a fire-extinguishing apparatus may be set in operation. r represents a valve in a water-pipe; L, a lever to

operate same; A, the cable; F, the projection to move the same on A, to which it is attached, being moved in such direction as to make contact between L and F.

Fig. 5 shows the operation of the lever S and lever bar or rod R on two of the respective cables A A at the points where are the clutches G G, allowing the weights W W to descend and close the shutters by moving the clutch G (see Fig. 3) clear of the projection H. Fig. 6 is a plan of part of the same arrangement.

Fig. 7 shows the connection of the cable to the shutter.

Having now described the method and machinery, we will illustrate its operation.

Suppose a building provided with our devices should take fire, moving the lever S releases all the weights, which, acting upon the cables, causes them to move, and, by the proper catch before referred to, the shutters are clutched and pulled down, so as to close them over the windows. At the same time the fire-extinguishing apparatus is set in operation and the building flooded with water or filled with flame-extinguishing gases, according to the character of fire-extinguisher employed in connection with the apparatus.

Having described our invention, what we desire to claim and secure by Letters Patent is—

1. In an apparatus for the prevention or extinguishment of fires in buildings, a fire-extinguishing device, in combination with shutters B, cable A, drop-weight W, rod R, and lever S, as herein shown and described. 85

2. In an apparatus for the extinguishment of fire, the cable A, weight W, or its equivalent, stop-catch G, and lever S, in combination with shutters D, substantially as and for the purposes set forth. 90

3. In an apparatus for the controlling and extinguishment of fires in buildings, the combination of a shutter of a building with a fire-extinguishing device, such shutter being closed by the operation of a cable and weight, as herein shown and described. 95

WM. H. MAXWELL.
